METHOD OF AND APPARATUS FOR SEPARATING, WASHING, AND GRADING LUMP MATERIALS

Hiram A. Holser, Pittsburg, Kans., assignor to
United Iron Works Company, Pittsburg, Kans.,
a corporation of Delaware

Application October 10, 1938, Serial No. 234,197

6 Claims. (Cl. 289—17)

This invention relates to a method of and apparatus for separating, grading and treating solid materials such as coal, and has for its principal object to provide a simple and efficient method and apparatus involving the flotation of the materials to be separated in a liquid medium having a specific gravity intermediate the specific gravities of the materials being separated.

Other objects of the invention are to provide a method and apparatus of this character wherein every particle of material is subjected to the flotation medium; to provide a method and apparatus resulting in less degradation incidental to processing; and to provide a method wherein the processing results in ultimate uniform products which may have dustless properties depending upon the nature of the flotation medium.

In accomplishing these and other objects of the invention, as hereinafter described, I have provided improved details of the structure, the preferred forms of which are illustrated in the accompanying drawings, wherein:

Fig. 1 is a vertical longitudinal section through a coal treating apparatus embodying the features of the present invention.

Fig. 2 is a plan view of the apparatus.

Fig. 3 is a section through the heavy material or slag removing conveyors taken on the line 3—3 of Fig. 2.

Fig. 4 is an enlarged cross-sectional view on the line 4—4 of Fig. 1.

Fig. 5 is a cross-section on the line 5—5 of Fig. 1.

Fig. 6 is an end elevational view of the apparatus.

Fig. 7 is a fragmentary section through a modified form of apparatus.

Referring more in detail to the drawings:

1 designates an apparatus embodying the features of the present invention and which includes an elongated tank having side and end walls 2—3 and 4—5, the lower portions of the side walls being shaped to provide a plurality of legs 6 reinforced on their inner faces by upright members 7 varying in length toward the respective ends of the tank to connectingly mount bottom supporting members 8.

Carried in the bay formed between the second and third pair of legs nearest the end wall 4 is a transversely extending trough or hopper 9, having upwardly diverging sides 10 and 11 respectively connected with upwardly inclined bottom sections 12 and 13 which are supported on the members 8 to form the bottom of the tank.

The tank is liquid-tight and of sufficient height

to give the desired time for separation of the materials, and is of suitable length to accommodate a feed unit 14 carried above the inclined bottom section 12, and a desired number of draw-off units 15, the number of which depends upon the number of grades into which the material is divided. The feed unit includes a chute 16 having the sides 17 tapering outwardly toward the bottom so that the chute increases in cross-section from the top toward the bottom. The upper end of the chute has a hopper 18 through which the material to be acted upon is delivered from a suitable elevator 19. The lower end of the chute extends downwardly within the tank below the level of liquid carried therein and has an inclined bottom for directing the material into a reciprocating feeder 20.

In the illustrated instance the feeder includes a distributing platform 21 carried by wheels 22 that operate on rails 23 carried on the inclined bottom 12. The platform is of sufficient length to extend under the inclined bottom portion of the chute and to overlap the upper edge 10 of the trough 9 as clearly shown in Fig. 1. The front wall of the chute terminates short of the feeder platform to provide passage for the strata of material carried on the feeder.

Suspended in the tank by pairs of arms 24—25 is an apertured apron or screen 26, the upper ends of the pairs of arms being carried by cross shafts 27 having their ends provided with flanged wheels 28 operable on the tracks 29 formed on the rim of the tank. The respective pairs of arms are of different length to support the apron at an incline and in substantially parallel relation with the inclined bottom section 13, that is, the apron slopes upwardly from the end of the tank having the chute so that the material floats upwardly thereunder toward the opposite end. The apron extends completely across the width of the tank and moves in close proximity to the side walls thereof and has depending side flanges 30 and 31.

In order to effect a seal and prevent particles of the material floating upwardly between the side flanges of the apron and the side walls of the tank, I provide guard wings 32 and 33 fixed to the inner walls of the tank below the flanges and extending upwardly and inwardly as at 34 to terminate in flanges 35 and 36 overlapping the depending side flanges 30 and 31 of the apron. With this arrangement it is obvious that the material floating upwardly within the flotation medium is deflected by the guard wings and moved along the under side of the apron as later de-

scribed. The apron is of a length to extend from a point spaced from the chute 16 to the end wall 5, the spacing allowing for ample reciprocatory movement of the apron when the wheels are moved on their respective tracks.

Hinged along the upper edge of the outlet opening of the chute is a deflector 37 having a free edge 38 engaging under the forward edge 39 of the apron as shown in Fig. 1. Beginning preferably in spaced relation with the forward end of the apron are groups of apertures 40 with the apertures in the respective groups increasing in size toward the upper end of the apron, the respective groups of openings registering with collectors 41 for receiving the respective sized materials passing through the apertures to the respective off-take conveyors 42 whereby the ultimate products are moved from the machine.

In order to reciprocate the apron, the shafts 20 carrying the wheels 27 are connected by pitmans 43 with eccentrics 44, the eccentrics being mounted on a transverse shaft 45 having its ends journalled in suitable bearings on the side walls of the tank. The shaft 45 is driven by a pulley 25 46 fixed thereon and operable by a belt 47 from a prime mover such as a motor 48, as best shown in Fig. 1. The feeder 20 is operatively connected with the apron through arms 49 so that the feeder is actuated simultaneously therewith.

30 The collectors extend across the width of the tank and have upwardly sloping sides 50 terminating in spaced vertical wall portions 51 and 52 forming the side walls of the conveyor housings. The conveyors 42 are best illustrated in Fig. 5 and are shown as comprising endless belts 53 and 54 running over pairs of sprockets 55 and 56 located at the respective sides of the tank and mounted on shafts 57 and 58 and over sprockets 59 and 60 carried on a shaft 61 that is supported 35 in side wing extensions 62 of the vertical wall portions 51 and 52 as shown in Fig. 5. The conveyor belts are connected by spaced blades 63 to carry the material under baffle plates 64 that extend transversely across the top of the tank at 40 a point spaced below the normal level of liquid carried therein as shown in Fig. 5. The blades of the conveyors move the material upwardly along inclined perforated bottoms 65 that connect the wing extensions to discharge the material into 45 chutes 66. Spaced above the bottoms 65 and at the inner sides of the lower run of the conveyors, are plates 67 forming upward continuations of the plates 64. The upper runs of the conveyors move over plates 68 having side edges attached to the 50 upper edges of the wing extensions. Formed below the bottoms 65 are sumps 69 for collecting the liquid draining from the solid materials being moved across the apertures by the conveyor, the sump 69 having an outlet 70 by which the liquid 55 is returned to the tank or preferably to a suitable reconcentrating apparatus (not shown), from where the liquid, after being reconcentrated, is returned to the tank.

The conveyor belts are operated through the 60 shaft 61, the shaft being provided with a driving sprocket 71 driven by a belt 72 from a suitable power source indicated at 73. The side wall 2 of the tank is shaped to accommodate the bottom 65 of the respective off-takes and the opposite side wall 3 terminates in arcuate shaped extensions 74 conforming to the path of movement of the plates as they round the sprockets 55.

Movable in the bottom of the tank is a conveyor 75 comprising endless chains 76 and 77 connected by conveyor blades 78. The forward

ends of the conveyor chains operate over sprockets 79 that are mounted on a shaft 80 journalled in the side walls of the tank at a point above the trough 9. The opposite end of the conveyor moves through an opening 81 in the end wall 5, 5 through an inclined conveyor housing 82 and over sprockets 83 that are carried on a driven shaft 84 having its ends journalled in a hood 85 of the conveyor housing, the hood 85 discharging into a receiver 86. The upper run of the conveyor moves upwardly in the conveyor housing over a transverse partition 87 which terminates in a foraminated partition section 88 extending parallel with the bottom section 13 and terminating adjacent the sprockets 79 so that the middlings gravitating downwardly through the flotation medium are caught by the partition section 88 and carried by the upper run of the conveyor to the trough 86. The fine hutch material or sludge passes on through the section 88 and 20 is removed by the lower run of the conveyor and discharged into the trough 8. The conveyor removing the middlings is driven by a sprocket 89 on the shaft 84 through a chain 90 operating over a similar sprocket 91 on a power unit 92. 25

Formed in the bottom of the trough 8 is a channel shaped sump 93 in which is rotatably mounted spiral conveyors 94 and 95 having flights thereon arranged to feed the material from the center of the tank toward the sides thereof for discharge 30 through openings 96 and 97 into off-take conveyors 98 and 99. The off-take conveyors extend upwardly and rearwardly along the side walls of the tank and discharge into a receiving trough 100 by which the heavy precipitates are 35 discharged from the machine.

The modified form of the invention illustrated in Fig. 7 employs a mechanical feeder in place of the chute illustrated in the preferred form, comprising an endless belt 101 having blades 102. The conveyor inclines downwardly into the tank in the upper portion of an inclined chute 103 and terminates in a forwardly extending discharge end 104 terminating under the reciprocating apron 105. The material to be treated is delivered through a hopper 107 at the upper end of the conveyor housing and is discharged over a baffle 108 to settle into the flotation liquid from pressure of the coal resting in the lower strata. This coal will then float upwardly and be caught 50 by the blades to be carried downwardly thereby for discharge under the reciprocating apron, thereby assuring delivery of the coal into the tank when the mine run is not sufficient to maintain the required head in effecting submergence to the 55 depth necessary for direct delivery, as illustrated in the preferred form of the invention.

In using the preferred form of apparatus constructed and assembled as described for treating a material such as coal, the tank is filled with a flotation medium of heavier specific gravity than the coal, for example solutions of zinc or calcium chloride. Mine run or partly prepared coal is delivered by the conveyor 19 into the hopper 18 at a rate so that a sufficient head is carried 60 in the chute 16 to submerge the lower strata of the coal into contact with the feeder 20 which is reciprocated incidental to its connection with the apron. The chute 16, being larger at the bottom than the top, allows free movement of the coal 65 downwardly therein without danger of bridging or jamming of the coal. The coal, being discharged by the feeder through the outlet of the chute and of lighter specific gravity than the liquid, floats upwardly therein to contact with 70

75

the under side of the apron. The foreign material, such as rock, slag, and the like, being of heavier specific gravity than the flotation liquid, precipitates into the trough 9. The middlings, being lighter, are carried along in the liquid and gradually precipitate and are carried by the upper run of the conveyor 75 up the inclined partitions 88 and 87 for discharge into the trough 86, from which they are taken to a pulverizer and from there returned to the initial feed. The heavy foreign material collecting in the trough 9 is discharged by way of the spiral conveyors 94 and 95 and the conveyors 98 and 99 into the receiving trough 100. The slime or sludge settles through the foraminated partition onto the bottom of the tank from which the lower run of the conveyor carries it into the refuse trough 9. The coal gradually floats upward under the inclined apron and is kept in a constant state of agitation incidental to reciprocation thereof so that the smallest particles of coal move upwardly through the first group of apertures into the collector and are carried off by the corresponding conveyor. The pieces of coal too large to pass through the first group of perforations continue their movement under the apron and those that will pass through the next group are discharged into the collector of that take-off. The lumps of coal which are too large to pass through any of the apertures are discharged through the opening 109 in the upper end of the apron into the last take-off. The coal delivered by the off-take conveyors is freed of the flotation medium by draining thereof into the sump 69. If desired suitable sprays 110 may be directed on the coal as it is carried by the take-off conveyors so as to remove all of the flotation medium. The grades of coal discharged from the spout 66 are conveyed to suitable cars or storage bins.

40 Attention is directed to the fact that movement of the apron and the conveyors in the bottom of the tank maintain the flotation medium in a state of agitation to prevent settling out of any of the components making up the solution. 45 In order to assure that the tank is kept filled with the flotation medium to the point where the graded coal will rise to the conveyors 42, an excess amount of the medium is circulated to and from the tank in the direction of movement 50 of the coal, the medium being admitted by spraying it from a nozzle 111 discharging into the upper end of the chute 16, and the excess medium discharged through an overflow 112 at the rear end of the tank (Fig. 1).

55 What I claim and desire to secure by Letters Patent is:

1. In an apparatus of the character described, a tank, a flotation medium in the tank for effecting movement of materials according to their specific gravity relatively to specific gravity of said medium, a spout having outlet into the tank below the level of said medium and above the tank bottom for maintaining a head of material to be separated in said medium, means for delivering the material to the spout, a screen extending transversely of the tank in the path of rising material, means supporting the screen at an incline with respect to the surface of the medium in the tank so that the material is intercepted by the screen and moved toward the higher end thereof while retained in submergence, said screen having groups of differently sized openings to pass the material according to size, means for vibrating the screen, and means 70 located in the tank below the outlet of said spout

for removing material falling through said medium.

2. In an apparatus of the character described, a tank, a flotation medium in the tank having a specific gravity intermediate the specific gravities of materials to be separated, a spout extending downwardly into the tank and discharging within said flotation medium for maintaining a head of the material to be separated by said flotation medium, means for delivering the material to the spout, a feeder at the bottom of the spout for carrying the material into the flotation medium, a screen extending transversely of the tank, means supporting the screen at an incline with respect to the surface of the medium in the tank so that the lighter material is intercepted by the screen and moved toward the higher end thereof, said screen having groups of differently sized openings to pass the material according to size, and a conveyor below said screen for collecting and removing the separated heavier material.

3. In an apparatus of the character described, a tank, a flotation medium in the tank for effecting movement of materials according to their specific gravities, means for delivering material into the tank below the surface of the flotation medium, a screen extending transversely of the tank and in the path of said material, means supporting the screen at an incline with respect to the surface of the medium in the tank so that the material is moved toward the higher end thereof, said screen having groups of differently sized apertures to pass the material according to size, conveying means in the bottom of the tank 25 for removing middlings, and means in the bottom of the tank for removing the heavy precipitating material.

4. In an apparatus of the character described, a tank, a flotation medium in the tank for effecting movement of materials according to their specific gravities, means for delivering lump material into the tank below the surface of the flotation medium, a screen extending transversely of the tank and in the path of said material, means supporting the screen at an incline with respect to the surface of the medium in the tank so that the material is intercepted by the screen and moved toward the higher end thereof, said screen having groups of differently sized apertures to pass the material according to size, and means in the bottom of the tank for removing the heavy precipitating material, including means for separating the heavy precipitants according to size.

5. In an apparatus of the character described, a tank, a separating solution in the tank having a predetermined specific gravity, means for introducing lump materials into the lower portion of the tank in submergence in said solution, a screen carried in the tank at a level above said introduction point and in submergence in said solution for passing selected size lumps of material rising through the solution and into contact with the screen, means for effecting movement of the rising material which is unable to pass through the screen to another portion of the tank, means for separately removing the lumps passed through the screen and the lumps which are unable to pass the screen, and means located in the tank below said introduction point for removing heavy material falling through said solution.

6. In an apparatus of the character described, a tank, a separating solution in the tank having

a predetermined specific gravity, means for introducing lump materials into the lower portion of the tank at a point submerged within said solution, a screen located in the tank in submergence in said solution and at a level above the introduction point of the materials, said screen having openings for passing predetermined sized lumps that ascend in the solution and through the solution above the screen to float on the ⁵
¹⁰ face of the solution, means for vibrating the

screen to effect movement of larger lumps of ascending material to another portion of the tank while floating in said solution, means separately removing the lumps passed through the screen and the larger lumps moved to said other portion ⁵ of the tank, and means located in the tank below said introduction point for removing heavy material falling through said solution.

HIRAM A. HOLZER. 10
